GAS BOMB

John Hays Hammond, Jr., Gloucester, Mass.

Application January 28, 1944, Serial No. 520,053

6 Claims. (Cl. 102—6)

1

This invention relates to gas bombs and more particularly to a gas bomb with a time controlled mechanism.

The invention provides means for controlling the emission of gas from a bomb so that the emission of the gas will start at a predetermined time after the bomb has struck its target.

The invention also provides means for making the detonating mechanism of the bomb inactive for a predetermined time after the bomb has been released.

The invention further provides means for automatically exploding the bomb if it is disturbed in the slightest from the position in which it came to rest after hitting the target.

The invention also provides means for exploding the bomb automatically at the end of a predetermined time, which is preferably several days.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Figure 1 is a section thru the bomb showing the control mechanisms; and

Figure 2 is a plan view of the sensitive mechanism for detonating the bomb if disturbed.

Like reference characters denote like parts in the several figures of the drawing.

In the following description parts will be identified by specific names for convenience, but they are intended to be as generic in their application to similar parts as the art will permit.

Referring to the accompanying drawings and more particularly to Fig. 1 a bomb 11 is provided with a steel casing 12. The interior of the bomb is divided into three compartments 13, 14 and 15 by means of two transverse bulkheads 16 and 17.

In the compartment 13 is the explosive charge 18 and a detonator 19. In the compartment 15 is a compressed gas, which may be either in the liquid or gaseous form. The compartment 15 is connected by a pipe 21 to a chamber 22, which in turn is connected by a plurality of pipes 23 to orifices 24 in the casing 12. Connected in the pipe 21 is a valve 25 which is provided with a valve stem 26 to which a collar 27 is attached. Between the collar 27 and the bulkhead 17 is mounted a compression spring 28.

In the chamber 14 is mounted a time mechanism 31 which is provided with a cam 32 to which is attached a pin 33. The cam 32 is made of insulating material and is provided with a notch 30.

2

and a contact segment 34, which at suitable times engages contacts 35 and 36. Engaging the pin 33 is an arm 37 of conducting material which is pivoted at 38. A spring 39 tends to move this arm to the left. Two contacts 41 and 42 are provided which are engaged by the arm 37 when in its left hand position. Engaging the cam 32 is a rod 43 which is slidably mounted in brackets 44. Secured to the rod 43 is a collar 45 between which and one of the brackets 44 is mounted a compression spring 46 which tends to hold the rod 43 against the cam 32. The right hand end of the rod 43 engages the collar 27.

Connected to the chamber 22 is a cylinder 47 in which is mounted a piston 48 provided with a piston rod 49 to the lower end of which is attached a contact bar 51 which co-operates with two contacts 52 and 53. A compression spring 54 is located in the cylinder 47.

20 Mounted in the chamber 14 is a contact mechanism 57. The contact mechanism 57 comprises a hemispherical bowl 63 (Figs. 1 and 2) provided with a top 64, the bowl and top being made of nonconducting material. The bowl is secured to 25 a ring 65 which is pivotally mounted in a gimbal ring 66, which in turn is pivotally mounted in brackets 67.

Secured to the ring 65 is a pivot 68, rotatably mounted in the gimbal ring 66, to the end of 30 which is secured a friction disc 69. Mounted on a bracket 71, which is secured to the gimbal ring 66, is a solenoid 72 provided with a core 73. Secured to the core 73 is a collar 74 between which and the solenoid 72 is mounted a compression spring 75. Mounted on the gimbal ring 66 is a spring 76, which is held out of engagement with the friction disc 69 by means of the core 73. A weight 70 mounted on the gimbal ring 66 counterbalances the weight of the solenoid 72, etc.

40 Secured to the gimbal ring 66 is a pivot 77 where a similar construction is provided including a spring 78 which is controlled by a solenoid 79. The winding of the solenoid 72 is connected by a flexible conductor 81 to one side of a battery 83 and by a flexible conductor 82 to the contact 41. The other side of the battery 83 is connected by a conductor 80 to the arm 37. The winding of the solenoid 79 is connected by branch conductors 84 and 85 to the conductors 81 and 82 respectively.

55 Mounted in the top 64 of the bowl 63 are four contacts 86 which are connected together and by a flexible conductor 87 to the arm 37. The bowl 63 is filled with mercury 88 or other conducting liquid, to a level just below the contacts 86. Projecting into the mercury 88 is an electrode 89 which is connected by a flexible conductor 91 to the contacts 36 and 53 and by branch conductor 92 to the detonator 19. The contact 42 is connected by a conductor 93 to one side of a bat-

tery 94 the other side of which is connected by a conductor 95 to the detonator 19. The contacts 35 and 52 are connected by branch conductors 96 and 97 to the conductor 93.

In the operation of this invention when the bomb 11 is released from the airplane the time mechanism 31 is started by any suitable means not shown. When the bomb strikes the target it will not explode, as the circuit to the detonator 19 is open. After the bomb has come to rest the contact device 57 will assume a horizontal position, as it is suspended in the gimbal ring 66.

After a predetermined interval of time has elapsed, for example four hours, the disc 32 together with the pin 33 will have rotated sufficiently in a clockwise direction, as indicated by the arrow, to release the arm 37, which will be moved to the left under the action of the spring 39, thus engaging the contacts 41 and 42. This will close a circuit from the battery 83 thru the solenoids 72 and 79, the cores of which will be retracted, thus releasing the springs 76 and 78 which will clamp the contact device 57 in whatever horizontal position it has assumed with respect to the bomb 11. In this position the contacts 86 will be just clear of the surface of the mercury 88.

If any attempt is made to tamper with the bomb and it is moved ever so slightly from the position in which it came to rest the mercury 88 will engage one of the contacts 86 thus completing a circuit from the battery 94, conductor 93, contact 42, arm 37, conductors 80 and 81, contacts 86, mercury 88, electrode 89, conductors 91 and 92, detonator 19 and conductor 95 back to battery 94. This will cause the detonator 19 to explode which in turn will cause the detonation of the explosive charge 18.

If the bomb is not thus exploded the disc 32 will continue to rotate until the notch 30 releases the rod 43 which will be moved to the left under the action of the spring 46 thus releasing the valve stem 26 which will be moved downward under the action of the spring 28. This will open the valve 25 thus allowing the gas from the compartment 15 to pass to the chamber 22 from which it will pass thru pipes 23 and orifices 24 to the exterior.

If all the orifices 24 are plugged up or otherwise closed so that the gas cannot escape a pressure will be built up in chamber 22 which will cause the piston 48 to move downward until the contact bar 51 engages the contacts 52 and 53. This will cause a circuit to be closed from the battery 94, conductors 93 and 97, contact 52, bar 51, contact 53, conductors 91 and 92, detonator 19 and conductor 95 back to battery 94. This will cause the detonator 19 to explode which in turn will cause the detonation of the explosive charge 18.

By varying the positions of the notches 30 in various bombs of a salvo it is possible to cause one bomb after another to give off gas, so that a continuous emission of gas may be obtained over a long period of time from one salvo of bombs. If the emission of the gas is interfered with the bomb will be exploded.

If the bomb is not otherwise exploded after a predetermined period, which for example may be several days, the disc 32 will have rotated sufficiently so that the segment 34 will engage the contacts 35 and 36. This will close a circuit from the battery 94, conductors 93 and 96, contact 35, segment 34, contact 36, conductors 91 and 92, detonator 19 and conductor 95 back to the battery 94. This will cause the detonator 19 to ex-

plore which in turn will cause the detonation of the explosive charge 18.

It is thus seen that a system is provided in which a salvo of bombs may be planted on a target and each bomb in succession will give off gas, thus causing the gas attack to be extended over a long period of time. If the emission of gas is prevented or if the bombs are tampered with they will explode. If not otherwise exploded they will be automatically exploded at the end of a predetermined period.

Although only a few of the various forms in which this invention may be embodied have been shown herein, it is to be understood that the invention is not limited to any specific construction but may be embodied in various forms without departing from the spirit of the invention as defined by the appended claims.

What is claimed is:

20 1. A gas bomb comprising a source of gas and an explosive charge, a detonator for said charge including a detonating circuit to actuate said detonator when energized, an open passage connected to said source for releasing said gas, a normally open valve controlling the flow of gas through said passage, a latch member latching said valve in closed position, timed means to release said latch member for opening said valve to release said gas, and a pressure switch actuated in response to excessive gas pressure in said passage, said switch being connected to close said detonating circuit so as to explode said charge when discharge of said gas is prevented to an extent to build up pressure in said passage.

25 2. A gas bomb comprising a source of gas and an explosive charge, a detonator for said charge including a detonating circuit to actuate said detonator when energized, a passage for releasing said gas, a normally open valve controlling the

30 flow of gas through said passage, a latch member latching said valve in closed position, timed means to release said latch member for opening said valve to release said gas, a pressure switch actuated in response to excessive gas pressure in said passage, said switch being connected to close said detonating circuit so as to explode said charge when discharge of said gas is prevented to an extent to build up pressure in said passage.

35 4. A gas bomb comprising a source of gas and an explosive charge, a detonator for said charge including a detonating circuit to actuate said detonator when energized, a passage for releasing said gas, a normally open valve controlling the flow of gas through said passage, a latch member latching said valve in closed position, timed means to release said latch member for opening said valve to release said gas, a pressure switch actuated in response to excessive gas pressure in said passage, said switch being connected to close said detonating circuit so as to explode said charge when discharge of said gas is prevented to an extent to build up pressure in said passage, and timed means to close said detonating circuit at the end of a predetermined time for destroying said bomb.

40 5. A gas bomb comprising a source of gas and an explosive charge, a detonator for said charge including a detonating circuit to actuate said

45 detonator when energized, a passage for releasing said gas, a normally open valve controlling the flow of gas through said passage, a latch member latching said valve in closed position, timed means to release said latch member for opening said valve to release said gas, a pressure switch actuated in response to excessive gas pressure in said passage, said switch being connected to close said detonating circuit so as to explode said charge when discharge of said gas is prevented to an extent to build up pressure in said passage, and timed means to close said detonating circuit at the end of a predetermined time for destroying said bomb.

50 6. A gas bomb comprising a source of gas and an explosive charge, a detonator for said charge including a detonating circuit to actuate said

55 detonator when energized, a passage for releasing said gas, a normally open valve controlling the flow of gas through said passage, a latch member latching said valve in closed position, timed means to release said latch member for opening said valve to release said gas, a pressure switch actuated in response to excessive gas pressure in said passage, said switch being connected to close said detonating circuit so as to explode said charge when discharge of said gas is prevented to an extent to build up pressure in said passage, a gravity controlled switch mounted to be closed in response to tilting movement of said bomb, and timed means connecting said last switch in said detonating circuit for closing the same when said bomb is disturbed.

60 7. A gas bomb comprising a source of gas and an explosive charge, a detonator for said charge including a detonating circuit to actuate said detonator when energized, a passage for releasing said gas, a normally open valve controlling the

flow of gas through said passage, a latch member latching said valve in closed position, timed means to release said latch member for opening said valve to release said gas, a pressure switch actuated in response to excessive gas pressure in said passage, said switch being connected to close said detonating circuit so as to explode said charge when discharge of said gas is prevented to an extent to build up pressure in said passage, timed means to close said detonating circuit at the end of a predetermined time for destroying said bomb, a liquid contact gravity controlled switch, means mounting said gravity switch for universal movement to assume a horizontal position with its contacts open when the bomb comes to rest, and timed means locking said gravity switch in its position of rest so that tilting movement of said bomb thereafter will close its contacts, said timed means also connecting said gravity switch in said detonating circuit.

5. A gas bomb comprising a source of gas and an explosive charge, a detonator for said charge including a detonating circuit to actuate said detonator when energized, a passage connected to said source, said passage having a discharge opening to the surrounding atmosphere for discharging said gas, and a pressure switch actuated in response to excessive gas pressure in said passage, said switch being connected to close said detonating circuit so as to explode said charge when discharge of said gas is prevented by restriction of said discharge opening to an extent to build up excessive pressure in said passage.

6. A gas bomb comprising a source of gas and an explosive charge, a detonator for said charge including a detonating circuit to actuate said detonator when energized, a passage connected to

said source, said passage having a discharge opening to the surrounding atmosphere for discharging said gas, a pressure switch actuated in response to excessive gas pressure in said passage, said switch being connected to close said detonating circuit so as to explode said charge when discharge of said gas is prevented by restriction of said discharge opening to an extent to build up excessive pressure in said passage, and timed means to close said detonating circuit at the end of a predetermined time for destroying said bomb regardless of the operation of said pressure switch.
